PARALLEL MATERIAL FLOW TYPE JAW
CRUSHER WITH LUBRICATING MEANS
WITHIN THE JAW

Maude E. Meinhardt, Los Angeles, Calif.

Application March 14, 1947, Serial No. 734,772

4 Claims. (Cl. 241—148)

1

This invention relates to rock crushing machines and has for its object to provide a simple and inexpensive machine capable of withstanding the severe strain such machines are subjected to during the rock crushing operation.

One of the difficulties encountered in the use of such machines is that the fine dust developed during the crushing operation settles in the moving parts of the machine thereby not only to affect the smooth operation of the machine but also subjecting it to excessive wear. In view of this, it is a further object of the invention to provide a machine that is so simple that it is comparatively easy to protect the bearings surfaces thereof from penetration of such fine dust and so substantially to prolong the life of the machine. These and other objects, as well as the many other advantageous features of the invention, will become apparent from the following detailed description and by referring to the accompanying drawings, of which:

Fig. 1 is a cross sectional view substantially through the center of a device embodying the invention;

Fig. 2 is a sectional end view of the machine taken on line 2—2 of Fig. 1;

Fig. 3 is an enlarged view of the center portion of the device appearing in Fig. 1.

Referring in the first instance to Fig. 1, the device illustrated comprises end plates 1 and 2, in combination with cross braces 3 and 4, which tie these two end plates together to form a solid framing. Pivot rods 5 and 6 bridge the space between the end plates, through which they extend and in which they are preferably tightly seated. Plates 7, 8 are fitted with perforated lugs at the top thereof which ride on the rods 5, 6 and the position of these plates is adjustable by means of set screws 11, 12 of the cross braces 3 and 4. When so mounted, these plates form the jaws of the device.

A crusher head 15 is mounted for oscillation within the framing, on a pivot shaft 16, and oscillations of this head are effected through the medium of an eccentric 17, which forms part of a shaft 18. The latter is mounted above the shaft 16 in parallel relation thereto, and it is by means of a pulley 19 connectable with a suitable prime mover. As the eccentric 17 rotates in response to rotation of the shaft 18, it is seen that oscillating movement is imparted to the crusher head about the pivotal shaft 16.

A suitable hopper 22 is affixed to the top of the frame members 1, 2, in which rock to be crushed is dumped in the first instance and from which

2

such rock settles between the faces of the crusher head and the inner surfaces of the jaws 7, 8. These spaces are adjustable by means of the screws 11, 12 to determine the size of the discharge openings 23, 24 at the bottom of the crusher head. The two jaws and the crusher head may be made from material hard and tough enough to withstand the pressure and grinding action of the descending rocks, or if not commercially practical to make the crusher head out of such hard material, it may be preferred to mount on the side faces thereof liners 25 and 26, which, when they begin to show wear, may be readily replaced.

15 The eccentric 17 is in this case set off a short distance from the vertical center line of the pivotal shaft 16 and it carries an arm 28 which is pivotally hung on a pin 29 seated in a stationary lug 30. Rotation of the shaft 18 imparts rocking movement of the head about the pivotal shaft 16.

An important feature of this modified device is that a large open space is provided within the crusher head 21 and this space forms a reservoir for suitable lubricants. One of the screws, by means of which the component parts of the crusher head are clamped together, is made tubular as indicated at 33 and the lower extension 34 of this screw reaches nearly to the bottom of the reservoir. Lubricants may be fed through this screw from time to time as required and a suitable plug 35 is driven or screwed into the entrance to the passage through the screw to seal it against dirt and dust carried by the rock lumps which are fed into the hopper 22. It is also important to note that a passage 32 carries lubricant to the pivotal shaft 16. In such manner, all the internal moving parts of the crusher head may be kept completely lubricated at all times and wear on the parts substantially eliminated.

40 When such combination is provided, it is found that the machine will operate smoothly and when the eccentric, the pivotal shaft and the pin 29 are seated in bearing bushings and the parts are all tightly fitted within the side plates of the machine it is found that little or no opportunity is afforded for fine rock dust to settle in the bearings.

While I have in the foregoing described preferred forms of the invention, I reserve the right to embody further modifications within the scope of the claims hereto appended.

I claim:

1. A rock crusher comprising, a casing having side plates and cross braces spanning the distance between said plates at the outer lower

corners thereof, a pair of rods extending through and fixed in said plates at the upper corners thereof, a pair of jaw members having perforated lugs at the top thereof rotatably mounted on said rods, means at the bottom of said members for adjusting the angular position thereof, a pivotal shaft centrally extending through said side members nearer the bottom thereof, a crusher head mounted for oscillation on said shaft, the interior of said head being hollowed out to form therein a lubricant reservoir, a drive shaft extending through the side plates and the crusher head above and to one side of said pivotal shaft, an eccentric on said drive shaft, a pin seated in the head parallel with the drive shaft on the other side of the head center line, and an arm riding on said eccentric and hung on the said pin.

2. A rocker crusher comprising, a casing having side plates and cross braces spanning the distance between said plates at the outer lower corners thereof, a pair of rods extending through and fixed in said plates at the upper corners thereof, a pair of jaw members having perforated lugs at the top thereof rotatably mounted on said rods, means at the bottom of said members for adjusting the angular position thereof, a pivotal shaft centrally extending through said side member nearer the bottom thereof, a crusher head mounted for oscillation on said shaft, the interior of said head being hollowed out to form therein a lubricant reservoir, a drive shaft extending through the side plates and the crusher head above and to one side of said pivotal shaft, an eccentric on said drive shaft, a pin seated in the head parallel with the drive shaft on the other side of the head center line, and an arm riding on said eccentric and hung on the said pin, a tubular member extending into said reservoir from the top of the crusher head, and a plug seatable in the entrance to the passage through said member.

3. A rock crusher comprising, a casing having side plates and cross braces spanning the distance between said plates at the outer lower corners thereof, a pair of rods extending through and fixed in said plates at the upper corners thereof, a pair of jaw members having perforated lugs at the top thereof rotatably mounted on said rods, means at the bottom of said members for adjusting the angular position thereof, a pivotal shaft centrally extending through said side members nearer the bottom thereof, a crusher head mount-

ed for oscillation on said shaft, the interior of said head being hollowed out to form therein a lubricant reservoir, there being a passage for lubricant from said reservoir to the said pivotal shaft, a drive shaft extending through the side plates and the crusher head above and to one side of said pivotal shaft, an eccentric on said drive shaft, a pin seated in the head parallel with the drive shaft on the other side of the head center line, and an arm riding on said eccentric and hung on the said pin.

4. A rock crusher comprising, a casing having side plates and cross braces spanning the distance between said plates at the outer lower corners thereof, a pair of rods extending through and fixed in said plates at the upper corners thereof, a pair of jaw members having perforated lugs at the top thereof rotatably mounted on said rods, means at the bottom of said members for adjusting the angular position thereof, a pivotal shaft centrally extending through said side member nearer the bottom thereof, a crusher head mounted for oscillation on said shaft, the interior of said head being hollowed out to form therein a lubricant reservoir, there being a passage from said reservoir to the said pivotal shaft, a drive shaft extending through the side plates and the crusher head above and to one side of said pivotal shaft, an eccentric on said drive shaft, a pin seated in the head parallel with the drive shaft on the other side of the head center line, an arm riding on said eccentric and hung on the said pin, a tubular member extending into said reservoir from the top of the crusher head, and a plug seatable in the entrance to the passage through said member.
